Primary Examiner — Richard Kearney

Assistant Examiner — Christina M. Dodson

(57) **CLAIM**

The ornamental design for lamp, as shown and described.

DESCRIPTION

FIG. 1 is a front, right, and bottom perspective view of a lamp, showing my new design;

FIG. 2 is rear and left perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is an enlarged view of the delineated region 9 in FIG. 1;

FIG. 10 is an enlarged view of the delineated region 10 in FIG. 1;

FIG. 11 is an enlarged view of the delineated region 11 in FIG. 1; and,

FIG. 12 is an enlarged view of the delineated region 12 in FIG. 2.

The lamp is shown with a symbolic break in its length. The appearance of any portion of the article between the break lines forms no part of the claimed design.

1 Claim, 12 Drawing Sheets
